GASOLINE DISPENSING PUMP

Herman H. Koopman, Cleveland, Ohio, assignor to The Standard Oil Company, Cleveland, Ohio, a corporation of Ohio

Application February 1, 1957, Serial No. 44,704

Term of patent 14 years

(Cl. D52—2)

Figure 1 is a perspective view of a gasoline dispensing pump viewed from the right hand side of the supporting end showing my new design; and

Figure 2 is a perspective view of the dispensing pump viewed from the right hand side of the other end.

I claim:

The ornamental design for a gasoline dispensing pump, as shown.
